United States Patent Office

Des. 198,053
Patented Apr. 21, 1964

198,053

JUG OR SIMILAR ARTICLE

Louis K. Warden, Laguna Beach, Calif., assignor to Purex Corporation, Ltd., Lakewood, Calif., a corporation of California

Substituted for abandoned design application Ser. No. 71,689, Sept. 14, 1962. This application Oct. 3, 1963, Ser. No. 76,969

Term of patent 14 years

(Cl. D58—5)

FIG. 1.

FIG. 2.

FIG. 4.

FIG. 3.

FIG. 5.

FIG. 1 is a side elevational view of a jug embodying my new design;

FIG. 2 is a left end elevation of FIG. 1;

FIG. 3 is a right end elevation of FIG. 1;

FIG. 4 is a top plan view of FIG. 1; and

FIG. 5 is a bottom plan view of FIG. 1.

I claim:

The ornamental design for a jug or similar article, substantially as shown.
